UNITED STATES PATENT OFFICE.

FREDERICK B. COOK, OF NEW YORK, N. Y.

MAIL-CHUTE.

1,294,381.

Specification of Letters Patent.

Patented Feb. 11, 1919.

Application filed November 5, 1915, Serial No. 59,820. Renewed May 28, 1918. Serial No. 237,174.

To all whom it may concern:

Be it known that I, FREDERICK B. COOK, a citizen of the United States, and a resident of the borough of Manhattan, in the city, county, and State of New York, have invented certain new and useful Improvements in Mail-Chutes, of which the following is a specification.

This invention relates to improvements in and relating to mail chutes having removable front walls, and has for its object to provide in such a chute an unobstructed inner surface, so that there will be no impeding or choking of the passage of mail therethrough, and which may be readily disassembled in sections when desired, to enable the same to be repaired or to remove mail caught therein. A further object is to provide such a chute which will be practically burglar-proof, and which will, when tampered with, become more firmly locked. A still further object is to provide such a chute which is simple in construction, and which is more efficient than such mail chutes previously in use.

With these and other objects in view, my invention is shown in the accompanying drawings, and will be hereinafter more fully described and finally pointed out in the claims.

In the drawings,

Figure 1 is a front elevation of a mail chute embodying my invention;

Fig. 2 is a section thereof taken on the line *a—a* of Fig. 1;

Fig. 3 is a front elevation of a portion of the chute with the front wall removed;

Fig. 4 is a rear elevation of a portion of the front wall;

Fig. 5 is a vertical section of a jamb with the front wall attached;

Fig. 6 is a sectional view of a modified form of construction; and

Fig. 7 is a sectional view of a still further modified form of construction.

Similar reference characters indicate corresponding parts throughout the several figures of the drawings.

Referring to the drawings, and more particularly to Figs. 1 and 2 thereof, a continuous channel comprising a rear portion 10, side portions 11 and 12 bent forwardly at right angles therefrom and having a slight resiliency, is provided at the forward ends 55 of the said side portions with inwardly bent forward portions 13 and 14 at each side of

the said chute, having their ends 15 and 16 forwardly bent to engage the glass panel of the front wall, as hereinafter described. The edges of the said bent forward portions 60 are beveled rearwardly and outwardly from their inner surfaces, as at 16', so that when any pressure is exerted on the front wall, there will always be a tight joint between the said wall and the said bent forward portions 65 at the inner surfaces of the latter. Channel members 17 and 18 are soldered, electrically welded, or otherwise suitably secured to the said forward portions, the inner faces of the said channel members being 70 inclined outwardly and forwardly, and the forward faces being provided with a plurality of openings 19 spaced longitudinally thereof. A top piece and cornice 20 are provided at the upper end of the said chute, 75 a base 21 is provided at the lower end thereof, and the front wall completes the same. The said wall is preferably formed in two sections each provided with a plate glass panel 22, and when these sections are 80 secured in place on the chute a locking bar 23 is placed between the same for preventing removal thereof.

The frame of the front wall comprises metal strips 24 and 25 of substantially U- 85 shape in cross-section, but having the inner leg of the U shorter than the other, and provided with a flanged portion 26 projecting inwardly at right angles therefrom, and is inclosed within a sheet-metal shell 27 90 which extends around the end of the outer portion of the said strip, and is inclined forwardly and inwardly to the same, as at 27'. The said shell extends outwardly and rearwardly from the inner portion to form 95 a channel 28 to receive the edge of the plate glass panel 22; when the front wall is in place, the said channels 28, or rather their rear walls, are covered by the forward portions 13 and 14 of the chute. Downwardly and rearwardly projecting hooked portions 35 are struck from the said strips 24 and 25 in spaced relation along the said walls and engage the openings 19 of the channel member 17 and 18, thereby securing 105 the front walls to the chute and permitting removal thereof by upward movement of the said front walls. The said hooked portions are slightly inclined from the said members 24 and 25, so that their inner faces 110 engage the said jambs and form a gradually tightening joint, as clearly shown in

Fig. 5. This joint is so formed that, under ordinary circumstances, the hooked portions do not rest on the bottom edges of the apertures 19, but when any undue pressure is exerted on the front walls either downwardly or rearwardly, they will, instead of becoming loose, gradually become tighter. In case the front wall is pressed rearwardly, this will bring the vertical ends of the hooks 35 slightly out of engagement with the adjacent faces of the channel members or jambs 17, 18, and the weight of the front wall will then tend to bring it down to such an extent as to cause the inclined portions 15 of the hooks 35 to engage the bottom edges of the openings 19 and produce a wedge action to force the front wall rearwardly into tighter engagement with said jambs. The resiliency of the forward portions 13 and 20 of the inclined portion 27^a of the shell 27 permits this. The removable locking bar 28 engages the lower end of the upper front wall and the upper end of the lower front wall, thereby locking the same in position. 25 A horizontal bar 29 is provided at the upper end of the upper wall, which engages the top portion 20, and a bar 30 is provided at the lower end of the lower wall, which engages the base 21. A suitable drop-opening 30 31 for insertion of mail in the chute is preferably provided in the lower wall below the locking bar.

In the form of construction shown in Fig. 6, the rear portions of the channel members 35 or jambs 17 and 18 are extended to the outer edges of the chute to form semi-circular resilient members 32, and the shells inclosing the outer portions of the U-shaped members 24 and 25 are bent inwardly and 40 forwardly to form resilient semi-circular members 33. In the form shown in Fig. 7, the forward portions 13 of the chute are bent rearwardly inwardly and forwardly at their ends to form channels 34, which, like 45 the members 15, 16 of Figs. 1 to 6, cover the rear walls of the glass engaging channels of the shells 27 and the joints of said rear walls with the jambs 17, 18. It will be seen that with these constructions, all 50 engaging parts are resilient, so that close joints are maintained, both at the inner and outer surfaces of the chute, at the inner surface for preventing cracks in which mail might be obstructed, and at the outer surface for preventing the entrance of chisels, jimmies, or other such tools that might be used to force the chute open. Those parts of the chute which are intended to remain in position when the front wall is removed, 55 may be included under the term "body."

I have illustrated and described preferred and satisfactory forms of my invention, but it is obvious that changes may be made therein within the spirit and scope 60 thereof, as defined in the appended claims.

I claim:—

1. An improved mail-chute, comprising a rear wall, side walls extending forwardly therefrom, forward portions extending inwardly from said side walls, a front wall 70 comprising a frame and a panel permanently mounted therein, said front wall being removable from said forward portions to obtain access to the interior of the chute, and resilient portions bent forwardly from 75 the said forward portions adapted to engage the inner side of the said panel of the front wall.

2. An improved mail-chute, comprising a rear wall, side walls extending forwardly 80 therefrom, forward portions extending inwardly from said side walls, a front wall comprising a frame, and a panel permanently mounted therein, said front wall being removable from said forward portions 85 to obtain access to the interior of the chute, and resilient portions bent forwardly from said forward portions, each provided with a beveled edge adapted to engage the inner side of the said panel of the front wall said 90 beveled edge adapted to maintain knife edge engagement with the interior side of said glass panel, upon pressure being applied at the outer side thereof.

3. An improved mail chute, comprising a rear wall, side walls bent forwardly therefrom, forward portions bent inwardly from the said side walls, resilient jambs provided on the said forward portions, a front wall adapted to engage the said forward portions, and to frictionally engage the said resilient jambs, and resilient portions bent forwardly from the said forward portions adapted to engage the inner side of the said front wall. 100

4. An improved mail chute, comprising a rear wall, side walls bent forwardly therefrom, forward portions bent inwardly from the said side walls, resilient jambs provided on the said forward portions, having 110 spaced openings longitudinally thereof, a front wall comprising side members resiliently engaging the said forward portions and provided with hooked portions adapted to frictionally engage the said openings of the said jambs to secure the front wall in place on the chute, and a glass panel carried between said side members, and resilient portions bent forwardly from the said forward portions adapted to engage the inner side of the said glass panel. 115

5. An improved mail chute, comprising a rear wall, side walls bent forwardly therefrom, forward portions bent inwardly from the said side walls, resilient jambs provided on the said forward portions, having spaced openings longitudinally thereof, a front wall comprising side members resiliently engaging the said forward portions and provided with rearwardly inclined 120 125 130

- hooked portions adapted to frictionally engage in a gradually tightening manner the said openings of the said jambs to secure the front wall in place on the chute, and a 5 glass panel carried between said side members, and resilient portions bent forwardly from the said forward portions adapted to engage the inner side of the said glass panel.
6. An improved mail chute, comprising a 10 rear wall, side walls extending forwardly therefrom, forward portions extending inwardly from said side walls, jambs on said forward portions, a front wall comprising a frame with side channels adapted to be 15 fitted between said jambs and a panel fitted into said channels, and resilient portions connected with said forward portions and having forwardly facing edges engaging said panel between the said channels.
- 20 7. An improved mail chute comprising a body provided with spaced jambs at its forward portion, and with resilient portions extending inwardly with respect to said jambs and having forwardly-facing edges, 25 and a front wall comprising a panel adapted for engagement by said edges, and a frame provided with side channels adapted to receive the sides of said panel and to be fitted between said jambs, the rear members of 30 each channel lying between the corresponding jamb and the panel-engaging edge of the adjacent resilient portion.
8. An improved mail chute comprising a body provided with spaced jambs at its forward portion, and with resilient portions extending inwardly with respect to said jambs and having forwardly-facing edges, 35 and a front wall comprising a panel and a frame with side channels adapted to embrace the sides of said panel and to fit between said jambs, the rear member of each channel engaging the rear face of the panel between the corresponding jamb and the panel-engaging edge of the adjacent resilient portion. 40
- 45
9. An improved mail chute comprising a body provided with spaced jambs at its forward portion, a front wall comprising a panel and a frame having side channels embracing the sides of said panel and fitting between said jambs, and members extending inwardly at the rear of said jambs and channels and covering the joints between the jambs and the respective channels. 50
10. An improved mail chute comprising a body provided with spaced jambs at its forward portion, a front wall comprising a panel and a frame having side channels embracing the sides of said panel and fitting between said jambs, and members extending inwardly at the rear of said jambs and channels and covering the joints between the jambs and the respective channels, said covering members engaging the panel between said channels. 55
11. An improved mail chute comprising a body provided with spaced jambs at its forward portion, a front wall fitted between said jambs, and resilient members on said body, extending inwardly and having forwardly-facing edges which engage the rear face of said front wall, said edges being beveled rearwardly and outwardly from their inner surfaces. 60
12. An improved mail chute comprising a body provided with spaced jambs the inner surfaces of which converge rearwardly, a front wall having members fitted between said converging surfaces, and portions extending inwardly on the body in the rear of said front wall and covering the joints between the front wall and the jambs. 65
- In testimony that I claim the foregoing as my invention, I have signed my name in presence of two subscribing witnesses.
- FREDERICK B. COOK.
